[57] CLAIM

The ornamental design for a nursery organizer, as shown.

DESCRIPTION

FIG. 1 is a perspective view of a first embodiment of a nursery organizer embodying our design;
 FIG. 2 is a front elevational view thereof;
 FIG. 3 is a right side elevational view thereof;
 FIG. 4 is a left side elevational view thereof;
 FIG. 5 is a rear elevational view thereof;
 FIG. 6 is a top plan view thereof;
 FIG. 7 is a bottom plan view thereof;
 FIG. 8 is a perspective view of a second embodiment of a nursery organizer embodying our design;
 FIG. 9 is a front elevational view thereof;
 FIG. 10 is a right side elevational view thereof;
 FIG. 11 is a left side elevational view thereof;
 FIG. 12 is a rear elevational view thereof;
 FIG. 13 is a top plan view thereof;
 FIG. 14 is a bottom plan view thereof;
 FIG. 15 is a perspective view of a third embodiment of a nursery organizer embodying our design;
 FIG. 16 is a front elevational view thereof;
 FIG. 17 is a right side elevational view thereof;
 FIG. 18 is a left side elevational view thereof;
 FIG. 19 is a rear elevational view thereof;
 FIG. 20 is a top plan view thereof; and,
 FIG. 21 is a bottom plan view thereof.
